Primary Examiner — W. A. Teddy Falloway(57) **CLAIM**

The ornamental design for a double accessory pocket for a golf bag, as shown and described.

DESCRIPTION

FIG. 1 is a first perspective view of a double accessory pocket of a golf bag;

FIG. 2 is a second perspective view thereof;

FIG. 3 is a first side view thereof;

FIG. 4 is a second side view thereof;

FIG. 5 is a front view thereof;

FIG. 6 is a rear view thereof;

FIG. 7 is a top view thereof; and,

FIG. 8 is a bottom view thereof.

The broken lines shown illustrate environmental structure and form no part of the claimed design.
